DESIGN FOR A SCALE CASING

Robert Heller, New York, N. Y., assignor to The Jacobs Bros. Co. Inc., Brooklyn, N. Y., a corporation of New York

Application August 10, 1939, Serial No. 86,583

Term of patent 7 years

To all whom it may concern:

Be it known that I, Robert Heller, a citizen of the United States, residing at New York, county and State of New York, have invented a new, original, and ornamental Design for a Scale Casing, of which the following is a specification, reference being had to the accompanying drawing, forming a part thereof, wherein:

Fig. 1 is a top plan view of a scale casing showing my new design;

Fig. 2 is a side view thereof; and

Fig. 3 is a front edge view thereof.

I claim:

The ornamental design for a scale casing, as shown.

ROBERT HELLER.
